(57) **CLAIM**

The ornamental design for a display screen or portion thereof with multi-state graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with multi-state graphical user interface showing a first state of the multi-state graphical user interface showing the claimed design;

FIG. 2 is a second state thereof;

FIG. 3 is a third state thereof;

FIG. 4 is a front view of another embodiment of a display screen or portion thereof with multi-state graphical user interface showing a first state of the multi-state graphical user interface showing the claimed design;

FIG. 5 is a second state thereof; and,

FIG. 6 is a third state thereof.

The broken lines in the figures show a display screen or portion thereof, and form no part of the claimed design.

The appearance of the multi-state graphical user interface changes between the images shown in FIGS. 1-3 and FIGS. 4-6, respectively. The process or period in which one image changes from one state to another forms no part of the claimed design.
